UNITED STATES PATENT OFFICE.

EDWARD E. JOHNSON, OF ST. PAUL, MINNESOTA.

RAILWAY WATER-COLUMN.

1,378,236.

Specification of Letters Patent. Patented May 17, 1921.

Application filed December 1, 1916. Serial No. 134,474.

To all whom it may concern:

Be it known that I, EDWARD E. JOHNSON, a citizen of the United States, residing at St. Paul, in the county of Ramsey and State 5 of Minnesota, have invented certain new and useful Improvements in Railway Water-Columns, of which the following is a specification.

My invention relates to railway water 10 columns and has for its object to provide in a water column structure a novel and highly efficient combination of curved delivery nozzle and discharge spout which will be economical to manufacture, install and 15 maintain, which will be adapted to serve locomotive tenders of widely varying heights, which will facilitate the flow of water through the standpipe and into the locomotive tender whatever the height of the tender, 20 which will provide free and ready drainage after the water has been shut off and the spout restored to initial position, which may be easily and conveniently operated for any height of engine tender, and 25 which will certainly avoid difficulties from the formation of ice in winter.

My invention relates to that class of water columns in which a central revoluble standpipe is employed having integrally connected therewith a delivery nozzle and associated with the delivery nozzle a discharge spout which is movable relative to the delivery nozzle in such manner as to give flexibility and a considerable vertical range to 30 the delivery end of the spout. In constructions heretofore employed the discharge nozzle has been relatively short and extending at a comparatively sharp angle from the standpipe, and means independent of the 35 nozzle have been required for supporting, guiding and controlling the discharge spout. This has resulted not only in a more or less complicated and cumbersome mechanism for supporting the spout and in material difficulties in giving the discharge end thereof sufficient flexibility and vertical range to 40 meet service conditions, involving expensive mechanism to assemble, but also has necessarily resulted in decreasing the rate of 45 flow of water because of the sharp and tortuous bends involved, and also because of the great height necessary in order to obtain the requisite relative position of discharge nozzle and spout to meet requirements. My 50 invention consists in a simple combination 55 of devices which eliminates all of these diffi-

culties, namely, the provision of an extended naturally-curved discharge nozzle forming a direct continuation of the standpipe and extending outwardly therefrom a 60 major part of the distance necessary to bridge over from the standpipe to the locomotive tender, and of a delivery spout of materially larger diameter having the same 65 curve as the discharge nozzle and directly mounted upon and movable thereon. The two coordinating members thus form a broad continuous path of delivery from the standpipe to the manhole of the tender for either a high or low tender without any 70 separate or complicated supporting mechanism for the spout, with the elimination of sharp changes in the water course and with a reduction of several feet of maximum 75 height above rails of the highest delivery point of the water. It is a further feature 80 of my invention, and one which assures its practicability and efficiency, that the extended curved delivery pipe or nozzle, and the complementary curved discharge spout, 85 are constructed of sheet metal welded at all joints into perfect continuity. These members are cheap to construct, light, and therefore capable of being supported from the standpipe without any bracing, and are particularly easy to handle.

The curve of the delivery nozzle and the corresponding curve of the discharge spout may be on a simple arc having a radius of half or less than half the distance between 90 the center of the standpipe and the center of the track. I have found, however, that a more efficient construction is produced by making this curve along the lines of an Archimedean spiral or involute and forming the discharge spout with a similar curve along the top thereof and having its bottom extended along a chord of such curve so as to form a greatly expanded central portion to said spout. This results in a 95 greater downward dip of the end of the delivery pipe and to corresponding increased vertical range of the spout for a given head of water, and also a considerable lateral range for variant track centers, as will more 100 fully appear hereinafter.

Various features and combinations of my invention in its different details are more 110 fully and additionally pointed out and claimed herein, so that the full objects and advantages of my invention will more fully appear in connection with such detailed de-

scription thereof, and are particularly pointed out in the claims.

In the drawings, illustrating the application of my invention in one form,—

5 Figure 1 is a side elevation view of the preferred form of my invention, showing the discharge spout in different positions. Fig. 2 is a similar view of a construction having an arcuate curve of delivery pipe and top 10 of spout but with the chord formation of the under side of the spout. Fig. 3 is a view similar to Fig. 1 of a construction embodying a discharge pipe and delivery spout both normally curved on an arc having a radius 15 of half the distance between track center and center of standpipe. Fig. 4 is an elevation view of the construction shown in Fig. 1 which also corresponds substantially to similar views of the constructions of Figs. 2 20 and 3 taken along a plane passing through the curved delivery spout and pipe. Fig. 5 is a sectional detail taken on line 5—5 of Fig. 1. Fig. 6 is a part sectional view showing more in detail some of the features of 25 the construction of Fig. 3. Fig. 7 is a section on line 7—7 of Fig. 6. Fig. 8 is a longitudinal section taken through the valve-operating mechanism of the construction shown in Figs. 2 and 3. Fig. 9 is a fragmentary detail view showing valve-operating 30 mechanism entirely outside of the standpipe. Fig. 10 is an additional part sectional view showing some modified features of the construction of Fig. 3.

35 The standpipe 10 is of usual construction supported in a base 11 so as to be revoluble therein and having a cap 12 protecting the junction of the base. Usual valve mechanism located at a suitable point below the 40 base (not shown) is operated by a valve rod 13 within the standpipe, as in Fig. 8, or 14 outside of the standpipe, as in Fig. 9. The end of the standpipe 10 may, as in Fig. 9, be provided with a flange 15, or it may terminate 45 with an uninterrupted externally-threaded portion 16 as shown in Fig. 8.

I provide a casting collar 17 formed with a lower peripheral flange 18 and an upper peripheral flange 19, and with a shaft 20 50 journaled in a portion of the collar 17. If an internal valve rod 13 is used the shaft will extend through stuffing-boxes of well-known construction, and since the same collar may be economically employed for either 55 external or internal valve construction, such stuffing-boxes will, in practice, be generally used. Fast on the shaft 20 is an internal arm 21 connected with the internal valve rod 13 as shown in Fig. 8, or an external arm 22 60 connected with the external valve rod 14, as in Fig. 9. And also fast to the shaft 20 are arms 23 and 24 of a U-lever 25 which extends upwardly and forwardly above the curved members hereinafter to be described.

65 A chain 26 depending from the U end of this

operating lever makes it readily practicable for the fireman to draw the same down, by which means the valve is operated. By means of a spring 47 in a housing 48 engaging a collar 49 on a rod 50 pivotally connected with arms 23 and 24 of the lever 25 said lever will be automatically restored to initial position, thereby operating to close the valves. This automatic returning may be effected also by the construction shown in Fig. 1 embodying a bail 51 secured rigidly to the shaft 20 and surrounding the outside of the standpipe 10 and carrying a weight 52 beyond such standpipe.

In case a standpipe in use has a flange 15 on the upper end, the member 17 is bolted thereto by its flange 18 as shown in Fig. 9, or in case the standpipe is plain at its end and externally threaded, the internally-threaded portion of collar 17 may be applied 80 thereto as shown in Fig. 8. This construction renders my invention practically effective for application to standpipes already erected wherein the nozzle-and-spout arrangement in use is unsatisfactory, and particularly in those numerous cases where because of change in locomotive practice the old water columns are not high enough to meet service conditions.

The delivery nozzle of my invention is 95 applied directly to the flange 19 of collar member 17 by means of a flange 27 which may, as in Figs. 9 and 10, be an integral part of a cast metal curved nozzle member 28, but which preferably, as in Figs. 1, 3 100 and 8, is associated with a separate cast collar member 29, to which in turn is welded a sheet metal delivery nozzle 60 or 30. The delivery nozzle, either that designated at 28 in Fig. 2 or that designated at 30 in Fig. 105 3, is curved on an arc which has a radius equal to or less than half the distance from the center of the standpipe to the center of the track, which corresponds to the center of the water holes of locomotive tenders. 110 Thus, if the standpipe were designed to be used between tracks spaced sixteen feet apart between centers of said tracks the distance from the center of the standpipe to the center of either track would be eight feet and 115 the delivery nozzle would be curved on a radius of substantially four feet. Furthermore, the nozzle so curved is extended so that it will reach well beyond the vertical plane parallel with the track midway between track center and standpipe center when the nozzle is turned at right angles 120 thereto. This is practicable with a comparatively low standpipe because in swinging a nozzle into operative position neither 125 it nor the spout carried by it, as will hereinafter appear, will need to be swung directly over the coal pile but will swing past the outer limits of the coal pile, where the coal cannot be much higher than the edge 130

of the tender wall. On the end of each of the nozzles described herein is permanently secured a member by means of which either the nozzle itself, or the nozzle and stand-pipe may be revolved. In practice I employ the bail 46 secured to and bridging the end of the nozzle and forming a loop which may be enveloped by the spout and which may easily be seized by the hand or hook 10 of the fireman.

Upon the curved nozzle 30 of Fig. 3 moves in telescoping fashion an enlarged discharge spout 31. This discharge spout will be substantially circular in cross section and several inches larger in diameter than the delivery nozzle and will be curved in exact conformity thereto, at least the upper peripheral line of the discharge spout will be so curved. The discharge spout 31 as 15 shown in Fig. 3 will preferably be formed of a multiplicity of transverse sections of sheet metal, such as galvanized iron, welded together at all joints 32 so as to form an integral curved member. This welding is performed in a well-known manner by what is 20 known as the acetylene welding process. The delivery nozzle 30 will likewise be preferably formed in the same manner, the lower section being welded to the collar member 29, as indicated at 33, and each succeeding section welded together as indicated at 34 in Fig. 8. The discharge spout 31 is wholly supported upon and by the delivery nozzle 30 and can readily be moved along 25 the same as desired by the brakeman or other operator. To facilitate this, a pair of arms 35 and 36 are employed extending from opposite sides of the end of the discharge spout, as best shown in Fig. 4. These arms 30 also are of advantage in supporting the spout upon the sides of the water hole when the same is in delivery position, as indicated at 37 for a high tender and at 38 for a low tender in Figs. 1, 2 and 3.

45 In the spout construction illustrated in Fig. 2, the delivery pipe 28 is given an arcuate curve similar to that of delivery pipe 30 of Fig. 3, and is shown as formed of a single piece of steel pipe properly curved. 50 The spout 40 is preferably formed of sheet metal in a manner similar to the spout 31, with the same curve along the top line and expanding in funnel shape from the discharge end to the rear thereof, excepting 55 that the bottom portion, as indicated at 41, is united along a chord of the arc, thus giving a larger amount of freedom of movement to the spout section relative to the end of the delivery pipe. A chain 39 is secured 60 to the inner side of the delivery pipe 28 as indicated at 42, and at the other end is secured to an eye 43 just back of a grab hook 44 carried upon the chord portion 41 of the spout 40. As clearly indicated in 65 dotted lines, when the spout 40 is in its

retracted position the chain will extend part way up into the spout and so be supported in a retracted position. When the spout is at its lowermost position as indicated in full lines in Fig. 2, the chain 39 will be 70 fully extended and will restrain outward lateral movement of the spout under any impulse due to the movement of water through the same. When the spout is used at a higher level the same effect is produced 75 by catching a portion of the chain in the grab hook at 44, as indicated in dotted lines at 45 of Fig. 2.

The preferred form of construction is illustrated in Fig. 1. In this construction 80 the discharge pipe 60 is not curved in the arc of a circle but, instead, is curved on the principle of an involute or Archimedean spiral, moving from the greatest radius at the point of connection to the standpipe to 85 the smallest radius at the end of the nozzle. This gives to the discharge end portion 61 of the delivery pipe a much more marked downward dip than can be secured from the same lateral extension on an arcuate curve. 90 The discharge pipe 60 preferably is provided with a top rib 62 of angle iron and an angle stop 63 at its extreme outer end, as best shown in Fig. 5. Carried by the curved delivery pipe 60 is a discharge spout 64 having 95 a circular discharge end 65, a top 66 curved in a manner conforming to the top curve of the pipe 60 and a somewhat oval or elongated rear opening 67, as best shown in Fig. 5. From the rear opening 67 to the circular 100 discharge end 65 the lower portion of the spout is extended along a straight chord line as indicated at 68. The interior of the spout therefore is expanding or of increasing size along its major axis from the rear opening 67 to a point transverse of the middle portion of the spout, from which portion the spout decreases in major diameter to the point of union with the circular discharge end 65, the minor diameter being varied little if any throughout so as to freely envelop the delivery pipe 60, as clearly indicated in 110 Fig. 5. A chain 70, secured at 71 to the inner side of spout 64 and passing over a roller or pulley 72 carried by a bracket 73 on the inner side of the curved delivery pipe 60, has connected to the free end thereof a weight 730 which always keeps the extent of chain between the spout and the pulley drawn tight. This restrains lateral movement of the lower end of the spout in any position and tends to hold the spout in its retracted position when the same is pulled back upon the curved delivery pipe as indicated in dotted lines in Fig. 1.

115 A chain 731 is also connected to an eye 732 on the under side of the delivery pipe 60 and to the rear end of the discharge spout 64 at the bottom thereof, as shown in Fig. 1. This chain limits movement of the 120 125

spout 64 in both its inward and outward positions, coming inside the spout when the spout is retracted into operative position and being outside the spout as shown in Fig. 5 1 when the spout is in its maximum outward position. Within and on the bottom wall of the spout 64 and close to the plane of the rear opening 67 is a lip 69 which is adapted to engage the stop 63 on the end of the delivery pipe and thus restrain the spout from moving off of the delivery pipe. Because of the enlarged rear opening into the spout relative to the discharge pipe, and the fact that this opening is of great length at and 10 near the center portions of the spout, the spout 64 may in any of its forward positions have a considerable range of swinging movement in the plane of the curved delivery pipe, and also laterally with respect 15 thereto. This gives a very great range of practically vertical movement of the delivery end 65. As indicated in Fig. 1, this range is from the lower manholes 75 up to the higher type of manholes indicated in 20 dotted lines at 76, but a still higher delivery is possible by reason of the fact that the manholes of high tenders are usually transversely elongated as indicated in the drawing, so that the spout 64 might be further 25 retracted on the delivery pipe 60 and swung upwardly to deliver into a considerably higher tender relatively than shown, if desired. In all of these positions the lower 30 wall or channel 68 of the spout will incline quite sharply from the point of delivery of 35 the delivery pipe thereinto, which taken in connection with the transverse expansion of the spout along its major diameter will always insure free, rapid and perfect drainage at the maximum capacity of the delivery pipe, without regurgitation, backing up or spilling. Arms 35 and 36 are applied to 40 spout 64 in the same manner as to spouts 31 and 40 heretofore referred to.

45 It will be understood that spouts 64 and 40, as well as spout 31, are preferably made from sheet metal fabricated and welded so as to make an integral member of the desired size and shape.

50 The spout 64, as shown in combination with the discharge spout 60, is wholly supported and slides upon the angle iron rib 62. This gives a very small area of supporting contact even when the spout is in contact 55 throughout its length. In practice the operator in pulling the spout out into position will seize the handles 35 and 36 and slightly lift the outer end of the spout so that the same will contact with the supporting surface of rib 62 only at a single point at the rear. This makes it practicable to move the spout outward into operative position very 60 easily and the oscillating movement is always readily accomplished by reason of the 65 fact that the longitudinal diameter across

any section of the spout is relatively large. Chain 70 in connection with weight 73 will always exercise sufficient restraint upon the end of the spout to prevent outward movement thereof when the free end is positioned 70 with the arms 35 and 36 resting upon the edges of the manholes as indicated in Fig. 1. If it is desired, the operator may additionally restrain the spout by stepping upon the chain and holding it with his foot, which 75 is useful particularly in the higher elevations of the spout. A stop 77 on the chain 73 may be used to restrain movement of the spout outwardly when the same is at any 80 usual delivery position.

As shown in Figs. 3 and 6 the spout 31, or for that matter any of the other forms of spouts if desired, may be provided with a roller 80 journaled on a pin 81 positioned at 85 the upper portion of the rear end of the spout, which roller is adapted to roll along the curved upper surface of the delivery pipe 30. A lever 82 which projects through a slot 83 in the wall of the spout 31 is also pivotally carried on the pin 81 and is also provided with a cam toe 84. When the lever is swung into the up position as indicated in Fig. 3, the cam toe 84 will be out of engagement with the delivery pipe 30 and thus will permit the roller 80 to support the rear end of spout 31 by contact with the top of delivery pipe 30. The rear end of the spout is also provided with a catch 85 adapted to engage any of a multiplicity of teeth 86 on a curved ratchet bar 87 secured to the bottom wall of the delivery pipe 30. When the lever 82 is in its up position the catch 85 will not engage any of the teeth 86, thus permitting the spout to be moved along the delivery pipe. The catch 85 will, however, engage a high tooth 88 on the outer end of bar 87, even when lever 82 is raised. By pulling down on lever 82 at any time the cam toe 84 operating against the upper wall of delivery pipe 30 will lift the rear of spout 31 and bring the catch 85 into engagement with any of the teeth 86, thus restraining further forward movement of the spout. When it is desired to restore the spout it is only necessary to push back on the same 100 and the cam toe will automatically swing out of engagement with the top of the spout and bring the lever into the up position of Fig. 3.

A modification is shown in Fig. 10 applied 105 to spout 40 and delivery pipe 28. Here a multiplicity of rollers 90 are provided along the top curve of the delivery pipe 28 upon which the spout 40 is supported and along 110 which it may roll freely. A weight 91 is connected by a cord 92 with the rear end of spout 40, preferably passing over the rollers 90 and a roller 93 carried by flange member 27, the several rollers being preferably 115 grooved to form a guide for cord 92. A 120

125 130

lever 94 is pivoted at the rear of the under side of spout 40 and is provided with a toe 95 adapted to engage a spring catch 96 and hold the same in position to engage with 5 the tooth 86 of the ratchet bar 87 whenever the lever 94 is pushed into its outer position. When it is drawn forward the spring catch 96 is released and the spout 40 may be restored to original position.

10 The purpose of curving the delivery nozzle along the line of an Archimedean spiral as shown in Fig. 1, is to obtain a sufficient downward dip to the end of the discharge nozzle to insure perfect flow and 15 drainage no matter how high the discharge spout may be raised or oscillated at its point of support upon the discharge nozzle. In this connection it is contemplated that a discharge spout of the type shown in Fig. 1 20 will be employed, and it must be borne in mind that the oscillation of such a discharge spout in a vertical plane not only permits great range of movement of the discharge end of the spout in a substantially vertical 25 line, but also, in combination with the discharge nozzle, makes practicable an in-and-out movement of the spout so as to adapt the same construction for use between track centers of varying width. This effect can perhaps be best obtained by the use of a nozzle 30 curved along the line of an Archimedean spiral. Substantially the same effect may, however, be obtained by the use of a discharge spout such as shown in Fig. 1 in combination with a nozzle having an arcuate 35 curve on a radius less than half of the distance between track centers, or by carrying the nozzle forward a substantial distance beyond the vertical plane parallel with the 40 tracks passing through the center of curvature. This will give the required downward dip to the delivery end of the nozzle and at the same time will provide the proper support for oscillation of the discharge spout 45 66 to enable it to be used for delivery of water through a varying horizontal as well as vertical range.

The advantages of my invention have been pointed out in considerable detail in connection with the description thereof. It will be apparent that by making a water-conveying member which bridges across my standpipe to the water hole out of a curved delivery pipe and a correspondingly curved 50 spout supported by and upon the delivery pipe, a structure of marked simplicity results which can be cheaply built and maintained. Furthermore, the broad and natural curve of delivery provided by this bridging 55 member is such as to facilitate exceedingly rapid flow of water, which is a matter of great importance in water-delivering devices of the type of my invention. Also, by using sheet metal both for the delivery pipe 60 and the curved spout, said sheet metal be-

ing integrally united at all junction points, preferably by acetylene welding, a structure which is light, strong and durable and which fully responds to the requirements of my invention will result. This structure has a 70 great range of movement of the discharge end of the spout in a substantially vertical line over the water holes of tenders on the tracks, has capacity for receiving and delivering from any sized standpipe the maximum flow of water possible of such a standpipe without spilling or regurgitation; can be operated with great ease and certainty and drains perfectly, obviating any chance of freezing or forming ice heaps. 75 80

I claim:

1. A railway water column comprising a standpipe having a curved delivery nozzle, and a correspondingly-curved discharge spout which together form a continuously- 85 curved water course of variable length.

2. A railway water column comprising a standpipe having a curved delivery nozzle, and a correspondingly-curved discharge spout which together form a continuously- 90 curved water course of variable length, said spout being slidably mounted on the discharge nozzle.

3. A railway water column comprising a standpipe, a removable section on the end of 95 said standpipe, valve-operating mechanism carried by said section, and a curved delivery nozzle detachably supported upon said section.

4. A railway water column comprising a 100 standpipe, a removable section on the end of said standpipe, a lever pivoted on said section, means operated by the lever to actuate valve mechanism, and a curved delivery pipe detachably supported upon the end of 105 the section.

5. A railway water column comprising a standpipe, a removable section on the end of 110 said standpipe, a shaft journaled in the section and connections therefrom for operating valve mechanism, a U lever having the arms thereof connected with said shaft on each side of the section and extending outwardly and forwardly, and a curved nozzle extending between the arms of the U lever. 115

6. A railway water column comprising a standpipe, a removable section on the end of 120 said standpipe, a shaft journaled in the section and connections therefrom for operating valve mechanism, a U lever having the arms thereof connected with said shaft on each side of the section and extending outwardly and forwardly, a curved nozzle extending between the arms of the U lever, and means for restoring the U lever and parts 125 connected therewith to initial position after operation thereof.

7. A railway water column comprising a standpipe terminating in a delivery nozzle 130 curved along the line of an involute or

Archimedean spiral, and a discharge spout coöperating therewith, the upper portion of said spout being correspondingly curved and the lower portion extending along a chord 5 of said curve.

8. A railway water column comprising a standpipe terminating in a delivery nozzle curved along the line of an involute or Archimedean spiral, and a discharge spout 10 having its upper portion correspondingly curved and engaging the upper portion of said nozzle and having its lower portion extending along a chord of said curve.

9. A railway water column comprising a 15 standpipe terminating in a delivery nozzle of circular cross section curved along the line of an involute or Archimedean spiral, and a discharge spout movable along and in oscillating relation to said nozzle, said 20 discharge spout loosely enveloping the nozzle and being relatively expanded between the respective ends of the spout.

10. A railway water column comprising a standpipe terminating in a delivery nozzle 25 of circular cross section curved along the line of an involute or Archimedean spiral, and a discharge spout movable along and in oscillating relation to said nozzle, said discharge spout loosely enveloping the nozzle 30 and being relatively expanded between the respective ends of the spout, said expanded portion extending in the plane of the discharge nozzle.

11. A railway water column comprising a 35 standpipe terminating in a curved delivery portion, a correspondingly-curved rib on the top of said delivery portion, and a spout engaging and supported by said rib and slidale therealong.

40 12. A railway water column comprising a standpipe terminating in a curved delivery portion, a correspondingly-curved rib on the top of said delivery portion, a spout engaging and supported by said rib and slidale 45 therealong, and a pair of arms extending outwardly in opposite directions from the discharge end of the spout.

13. A railway water column comprising a standpipe terminating in a curved delivery portion, a correspondingly-curved rib on the 50 top of said delivery portion, a spout engag- therealong, a pair of arms extending out- 55 wardly in opposite directions from the dis- charge end of the spout, and a flexible con- nector between the outer end of the spout and the standpipe for restraining lateral movement of the spout.

14. A railway water column comprising a standpipe having a curved delivery nozzle, 60 a correspondingly-curved discharge spout movably supported on and by the nozzle, and a chain connected to the nozzle and to the rear end of the discharge spout for limit- 65 ing movement of the discharge spout in both directions.

15. A railway water column comprising a revoluble standpipe terminating in a later- 70 ally-extended delivery portion; a bail secured to the end of said portion so as to bridge the open mouth thereof, and a dis- charge spout movable along said delivery portion and over said bail.

16. A railway water column comprising a revoluble standpipe terminating in a later- 75 ally-extended delivery portion, and a bail rigidly secured to the end of the delivery portion and bridging its open mouth by which the standpipe and said portion may be revolved.

17. A railway water column comprising a standpipe having a delivery nozzle with a 80 curved upper surface, a discharge spout enveloping said nozzle, and a roller journaled in the rear of said discharge spout 85 and engageable with said curved upper surface, said roller by engagement with said curved upper surface operating as the sole means of support of the spout while the same is being forwarded along the curved 90 nozzle.

In testimony whereof I affix my signature.

EDWARD E. JOHNSON.
